UNITED STATES PATENT OFFICE.

MARTIN NOAK, OF PITTSBURGH, PENNSYLVANIA.

RIVETING-TOOL OR DOLLY-BAR.

1,152,205.

Specification of Letters Patent. Patented Aug. 31, 1915.

Application filed May 11, 1915. Serial No. 27,361.

To all whom it may concern:

Be it known that I, MARTIN NOAK, a citizen of the United States, and resident of Pittsburgh, in the county of Allegheny and

5 State of Pennsylvania, have invented certain new and useful Improvements in Riveting-Tools or Dolly-Bars, of which the following is a specification.

My invention relates to the class of riveting tools known as dolly-bars and used in "bucking up" or holding rivets in position in the registering holes of the materials being connected by engagement of the head on one end of the rivet while a head is being 15 formed on the other end of the rivet to secure together the materials being riveted.

The invention more particularly relates to a dolly-bar used in cold riveting, in riveting sheeting, corrugated iron and similar 20 light materials with which the rivets used are soft metal rivets which are upset or are headed while cold. Such rivets usually are short and of small diameter and on account of the lack of length are difficult to insert 25 in the registering openings or holes, the fingers of the workmen generally being thick and clumsy. In inserting such rivets it has been the practice to position the rivet with one hand and to bring the dolly-bar 30 into engagement with the head on one end with the other hand of the workman, generally known as a "bucker-up."

One object of my invention is to provide a tool of the class described having novel 35 means for detachably holding the rivets on the dolly-bar and thereby enabling the dolly-bar to be used in positioning the rivets in the rivet holes preparatory to forming a second head on one end of the rivet, as is 40 done in such riveting operations.

Still further objects of my invention will appear as the novel construction and arrangement of the parts are more fully described hereinafter and specifically pointed 45 out in the appended claims.

Referring now to the drawings forming part of this specification, Figure 1 is a plan partly in section showing a dolly-bar constructed and arranged in accordance with 50 my invention. Fig. 2 is an end elevation of the dolly-bar shown in Fig. 1. Fig. 3 is a side elevation of one end of the dolly-bar showing the yielding means by which the rivets are detachably held in position on the 55 dolly-bar in applying the rivets to the holes

in which they are to be upset or headed. Fig. 4 is a plan showing a modification in the construction of dolly-bars made in accordance with this invention.

In the accompanying drawings, the numeral 2 designates the stem or shaft of the dolly-bar having heels 3 and 4 on the ends thereof, one of the faces 5 and 6 defining the ends of the dolly-bar being held in engagement with the head of the rivet while the rivet is being upset to form the second head thereon. In one of these faces 5 is a slot or recess 7 of a depth which is approximately equal to or slightly greater than the thickness of the flat head rivets, which is the 60 type of rivet with which the dolly-bar of my invention is particularly adapted for use.

On the side face 8 of the heel 3 of the dolly-bar is a slot or recess 9 which connects into the open end of the recess 7 in the face 5 of the dolly-bar and removably secured at one end in the groove 9 is a spring 10 having a bent outer end 11 which extends into the slot 7 in the end of the dolly-bar. The fixed end of the spring 10 is removably secured 65 to the dolly-bar by means of a cap screw 12.

In the modified construction shown in Fig. 4 the anvil or heel 5^a of the dolly-bar has a reduced shank 13 by which the heel is detachably secured on the stem 2^a, pieces of 70 wrought metal pipe of convenient length being conveniently used to form the detachable stems. In this construction the shoulder formed at the junction of the shank 13 with the heel 5^a forms means against which 75 the end of the pipe engages when the dolly-bar is in use.

In the use of my improved apparatus the flat head of the rivet 14 is placed in the recess 7 in the face 5 of the heel 3 and the edge of the bent end of the spring engages with its head and yieldingly holds the rivet on end on the dolly-bar. The dolly-bar is then used in piloting the rivet into the registering holes in which it is to be upset. When the rivet is within the holes the "bucker-up" will hold the rivet by means of the dolly bar while the riveter is upsetting the other end of the rivet to form a head, in the usual known manner. After the end of the rivet has been upset to such an extent that it will not drop out of the holes in which it is positioned, the other portion of the face of the heel or anvil 3 is brought 80 into engagement with the rivet head.

The advantages of my invention, which will be appreciated by those skilled in the art, arise from the simplicity of the rivet holding apparatus on the dolly-bar. The recess and the yielding spring on the end of the dolly bar enable the rivets to be detachably held with sufficient force to enable the rivets to be piloted and readily inserted in place by manipulation of the dolly-bar. The insertion of short rivets into the rivet holes is facilitated and the liability of pinching or other injury to the fingers of the workmen, as oftentimes occurs when the rivet is inserted with one hand while the dolly-bar is brought into holding position with the other in the manner heretofore employed, is avoided and overcome.

Modifications in the construction and arrangement of the parts may be made with-

Copies of this patent may be obtained for five cents each, by addressing the "Commissioner of Patents, Washington, D. C."

out departing from my invention as defined 20 in the claims.

I claim:—

1. A dolly-bar comprising a stem and a heel having a riveting face, and means on the end of said bar arranged to engage and 25 yieldingly hold a rivet in position on the heel of said bar.

2. A dolly-bar comprising an anvil face having a recess therein to receive the head of a rivet, and a spring movable within said 30 recess arranged to engage the rivet head and yieldingly hold the rivet on said anvil face.

In testimony whereof, I have hereunto set my hand.

MARTIN NOAK.
